DESIGN FOR A COOKING VESSEL OR SIMILAR ARTICLE

Harry B. Klusmeyer, Chicago, Ill.

Application March 22, 1939, Serial No. 83,755

Term of patent 14 years

To all whom it may concern:

Be it known that I, Harry B. Klusmeyer, a citizen of the United States and a resident of the city of Chicago, in the county of Cook and State of Illinois, have invented a new, original, and ornamental Design for a Cooking Vessel or Similar Article, of which the following is a specification, reference being had to the accompanying drawing, forming a part thereof.

In the drawing:

I claim:

The ornamental design for a cooking vessel or similar article, as shown.

HARRY B. KLUSMEYER.
